UNITED STATES PATENT OFFICE.

MAX VAN GÜLPEN, OF MÜLHEIM, GERMANY.

CIGAR-BUNCHING MACHINE.

SPECIFICATION forming part of Letters Patent No. 451,610, dated May 5, 1891.

Application filed June 3, 1890. Serial No. 354,126. (No model.) Patented in Belgium January 27, 1890, No. 89,304, and in Luxemburg January 30, 1890, No. 1,245.

To all whom it may concern:

Be it known that I, MAX VAN GÜLPEN, a subject of the King of Prussia, residing at Mülheim-on-the-Rhine, Kingdom of Prussia, have invented new and useful Improvements 5 in Cigar-Bunching Machines, (for which I have obtained Letters Patent in Belgium, January 27, 1890, No. 89,304, and in Luxemburg, January 30, 1890, No. 1,245,) whereof the following is a specification.

In the specification of the cigar-bunching machine for which the United States Patent No. 422,325, dated February 25, 1890, has been granted to me I have described a machine which works with an apron attached at 15 both extremities to a table, and a movable frame carrying a roller, by which the fillers, being placed in the bight of the apron and wrapped in the latter, are compressed with a 20 rolling action into a bunch. This bunch is enveloped in the binder and deposited by the apron in an open mold provided with a cover or hinged top part, which compresses the bunch and imparts to it the required form, 25 the closed mold being afterward removed from the machine and taken to the operator who puts on the wrappers.

According to my present invention I employ in place of single molds, as described 30 in my said former specification, a number of connected molds or a multiple mold so arranged as to be capable of rotating or otherwise traveling with a suitable step-by-step motion in front of the delivery end of the 35 table of the machine, so as to receive the bunches one after the other, thus obviating the inconvenience attending the previous arrangement and arising from the necessity for removing each mold separately and putting 40 another into position whenever a bunch is delivered from the table. The said multiple mold is composed of sections forming together a series of divided molding-cavities and so connected side by side to a carrier that 45 they may be shifted in transverse direction relatively to each other. When these sections are pushed close together and kept in this position, they are in the state for receiving the bunch and allowing the same to be compressed 50 therein by a counter-mold part, whereas when they are spread apart or shifted away from

each other they release the molded bunch so that it may then easily be removed.

The carrier to which the sections are connected may consist in a double traveling chain 55 running over two barrels or in a sliding frame or a rotating shaft. In the first arrangement the sections are so fixed or connected to the links of the chain as to be in contact with each other when the chain is 60 stretched out in a straight line, as is the case relatively to the parts of the chain being, during the motion of the chain, between the two barrels, the sections under these conditions spreading apart automatically as the 65 chain passes upon either barrel. In view of securely keeping the chain straight between the barrels it may be supported by guides. If the carrier is to consist in a sliding frame or a shaft, one or more clamps or key-pieces 70 are provided for, whereby the sections can be kept close together or released at will.

In Figures 1 to 7 of the annexed drawings a multiple-molding apparatus of my invention is represented, in which the mold-sections are 75 mounted on a shaft so as to form a cylinder. Fig. 1 is an end view showing the counter-mold piece and certain levers turned back. Fig. 2 is a plan corresponding to Fig. 1. Fig. 2nd is a sectional view of a detent mechanism. Fig. 80 3 shows the apparatus in end view with the counter-mold piece turned down into the uppermost cavity of the mold-cylinder and the said levers in operating position. Fig. 4 is a transverse section, and Fig. 5 a longitudinal 85 section, of the mold-cylinder. Fig. 6 shows in end elevation and in top view the counter-mold piece with parts to which it is fixed. Fig. 7 is a perspective view of three sections 90 of the mold-cylinder placed in their proper relative position, except that they are spread far apart, some portions being broken away. Fig. 8 is an elevation of the modified apparatus, in which the mold-sections are attached to chains running over two barrels. Fig. 9 is 95 a transverse sectional view thereof on line 1 2, Fig. 8. Fig. 10 shows in sectional elevation a multiple mold inclosed in a frame that serves as a carrier. Fig. 11 is a partial transverse section, and Fig. 12 a plan of the same. 100

The said mold-cylinder is composed of a plurality of sections *f*, forming on each side

one-half of a mold, and two sections $f' f^2$, having the form of a mold-half on one side only. All these mold-sections are provided with eyes i , Fig. 7, with which they are strung on the shaft w , and they are arranged to have so much play that when they are all pushed close together a space will be left between two of them, such as is shown in the drawings between the sections f' and f^2 . The section f' is preferably fixed to the shaft. By these means all the sections except the section f' are rendered capable of being rocked on the shaft and of being shifted laterally one after the other in view of spreading them apart and allowing the bunches deposited in the molds to be removed.

For the purpose of maintaining the sections f in contact with each other and with the sections $f' f^2$ during the operation of molding a wedge-like key-piece q is inserted into the space between the sections $f' f^2$. This key-piece is pivoted to the section f' and provided with an arm whereby it may be turned up and down, as shown in Fig. 5.

25 The described mold-cylinder is placed with its shaft w in bearings formed in a frame e , and which are so constructed as that the cylinder may be easily removed and exchanged for another one.

30 Opposite to the cylinder is pivoted to the frame e a plate t' , carrying the counter-mold piece t in such position that when the plate is swung toward the cylinder the piece t will engage with the uppermost molding-cavity thereof, (see Fig. 3,) while on the other side of the cylinder are mounted on a shaft g two lever-arms l , provided with handles and adapted to be turned down on the bar b^2 , fixed to the plate t' , this arrangement affording 40 convenient means for pressing the piece t down upon the bunch present in the said molding-cavity.

In order that previous to each molding operation the molding-cylinder may be arrested 45 in such position that one of its cavities is in the path of the counter-piece t when being swung over, a detent mechanism is provided for. This mechanism, as shown by the drawings, consists in a disk p , secured to the section f' , and a conically-pointed retaining-pin p' , guided in a sleeve p^2 and impelled by means of a spring p^3 against the disk p , which is furnished with holes for the pin to engage in, the said holes being so arranged that every 50 time the pin is in engagement with one of them the corresponding molding-cavity will be in the proper position for receiving a

bunch as well as the counter-mold piece t' , and the cavity will be kept in this position until the requisite rotative force is applied to the cylinder to cause the pin p' to be pushed back.

In the modified arrangement shown by Figs. 8 and 9 the mold-sections f^3 are fixed to the endless chains a , having pins b , which engage with teeth on the barrels or sprocket-wheels c . The mold-sections are guided during the upper part of their course by the bars d . h is a detent operating on the teeth of one of the wheels. 65

The second modification (represented by Figs. 10 to 12) also consists in mold-sections attached to chains; but the chain-mold thus produced is inclosed in a frame k , arranged to be opened at one end and provided with a 70 screw for pressing the sections together.

I claim as my invention—

1. For use in a cigar-bunching machine, a multiple bunching-mold composed of the sections $f' f^2$, forming together a series of divided molding-cavities, a shaft w , carrying the said sections, the sections f and f^2 having eyes with which they are strung on the said shaft, and the key-piece q , pivoted to one of the sections $f' f^2$ and adapted to be inserted 80 between the said sections $f' f^2$, in combination with a counter-mold piece t , fitting into the molding-cavities, and means whereby the said piece t is guided to engage with the cavity brought into the path of the same, substantially as specified.

2. For use in a cigar-bunching machine, a multiple bunching-mold composed of sections forming together a series of divided molding-cavities, a carrier to which the said sections 95 are connected, so as to be capable of transverse motion relatively to each other, and means for keeping the contiguous sections in contact with each other and for allowing them to be spread apart, in combination with a movable counter-mold piece fitting into the molding-cavities, means for guiding the said piece, and a detent mechanism whereby the bunching-mold is arrested whenever one of the molding-cavities has been brought into 105 the path of the counter-mold piece, substantially as set forth.

In testimony whereof I have hereunto set my hand in the presence of two subscribing witnesses.

MAX VAN GÜLPEN.
